PRECAST SECTIONAL CONCRETE STAIRS

Dale S. Seeber, Hillsboro, Oreg.

Application August 6, 1948, Serial No. 42,859

4 Claims.

(Cl. 72—96)

1

My invention pertains to precast sectional concrete structures, and relates particularly to concrete stairs constructed of precast sections which are joined detachably for ready assembly and disassembly.

It is a principal object of my invention to provide concrete stairs formed of sections which are precast in molds at a factory for subsequent assembly at the site of installation.

Another object is the provision of novel means for joining together precast concrete sections detachably to form solid concrete stairs.

These and other objects and advantages of my invention will appear from the following detailed description taken in connection with the accompanying drawing in which:

Fig. 1 is a perspective view of a stairs constructed of precast concrete sections embodying my invention, and showing in dotted outline means by which said sections are joined together;

Fig. 2 is a side elevation of the stairs shown in Fig. 1 and illustrating in dotted outline a modified form of means for joining the precast sections together;

Fig. 3 is a fragmentary elevation of the structure shown in Fig. 2 as viewed in the direction of arrow 3; and

Fig. 4 is a fragmentary sectional view of the step sections embodying my invention and showing a further modification of means for joining said sections together.

In the stair construction embodying my invention plates 1 and 2 form a base upon which the sidewalls 3 and the lowermost of the step units 4 are detachably mounted. Although I have shown plates 2 as being of narrow slab construction and arranged individually under each of the sidewalls 3, it is understood that a plate having the same lateral dimension as plate 1 may be used. In fact, a single base plate may be used to advantage in some constructions in place of the plural plates 1 and 2. A recess is formed in the base plate 1 and extends laterally thereacross a distance equal to the length of a step unit 4. Said recess is triangular in cross section and functions to secure the lower step unit in position, as is more fully explained hereinafter.

The sidewalls 3 are mounted in spaced relation upon the base plates 1 and 2. As shown in the drawing, the sidewalls are of trapezoidal shape, the shorter of the two parallel sides being provided for mounting a platform 5 adjacent the uppermost step 4. In the event that said platform is not desired, the sidewalls may be of triangular shape. In either case a sloping edge is provided for mounting the step units 4 in position. The sidewalls may be secured detachably to the base plates 1 and 2 by means of dowels 6, (as is illustrated in Fig. 2) which are imbedded in the sidewalls and project from the lower edge thereof into wells formed in the base plates.

These are provided as a detent means facilitating ready assembly of the stairs. Dowels 6 are also provided to join the base plates 1 and 2 together in abutting relationship.

2

These dowels serve also to join the base plates together in abutting relationship.

Each of the step units 4, which includes the riser portion 7 of each step, is substantially trapezoidal in profile. The sloping edge of the step unit rests upon the sloping edge of the sidewalls 3, thereby forming a horizontal stepping surface 8 which is parallel with the base plates 1 and 2.

The platform 5, if provided, preferably is of the same thickness as the thinner end of the step unit against which it abuts. The stepping surface 8 of the step and the upper surface of the platform thus lie in a common plane to form an upper landing on the stairs.

A portion of the riser adjacent the sloping side of the step is cut away longitudinally to form a squared notch. On the step units above the lowermost step, this notch overlaps the rear edge of the step immediately below it, and the portion of the unit adjacent the notch serves as a key by which the step units are held releasably in assembled condition. On the bottom step the key portion adjacent the notch is received in the triangular recess formed in the base plate 1.

It is to be noted that the floor of the recess forming the hypotenuse of the triangle is an extension of the upper face of sloping edge of the sidewalls 3. In this manner the lower step rests against the sloping edge of the recess and the sidewalls and is detachably locked to the base plate whereby it is prevented from being displaced laterally or longitudinally therefrom. Although the step units arranged above the lowermost step cannot move longitudinally with respect to the sidewalls 3, they may, if not restrained, be displaced laterally thereof. I prevent this lateral displacement by any of the various means illustrated in the drawing and now to be described.

Referring to Fig. 1 of the drawing, the base plate 1, the step units 4 and the platform 5 are provided with holes which align with each other when the sections are arranged together to form the stairs. A length of wire 9 is passed through said aligned holes during assembly of the sections and is thereafter joined at its ends to form a closed loop. Wire 9 may be formed integral with base plate 1, as shown in Fig. 1, or may be threaded therethrough, as above described, although the latter procedure would, of course, require the preformed hole in base plate 1 to be rounded to facilitate ease of assembly. A groove 10 is formed longitudinally in the rear edge of the platform to receive the wire therein and conceal it from view. The rear edge of the platform thus presents a flat surface for abutment against structures on which the stairs are to be installed.

The modification illustrated in Fig. 4 of the drawing differs from the construction shown in Fig. 1 only in the provision of elongated tubes 11 in place of the holes formed in the concrete or

other material from which the sections are constructed. The tubes 11 are molded into the sections during the casting operation, and thus form an integral part of each unit. In addition to providing the necessary aperture through which the wire may be threaded, the tubes enhance the structural strength of the sections in which they are secured. Spike-like extensions 11a are inserted in one end of each of the tubes and slidably engage the bore of adjacent tubes.

In the modification illustrated in Figs. 2 and 3, the step units 4 are provided with dowels 12 which extend parallel with the sloping side of the former and project outwardly from the squared notch. These dowels are received in wells formed diagonally in the rear corners of the step units and in the base plate 1 adjacent the triangular recess. As each step unit is slid downwardly along the sloping edges of the sidewalls 3, the dowels 12 enter the complementary wells provided, and the units thus become locked detachably in assembled arrangement. U-shaped dowels 13 embedded adjacent each end of the platform 5 project into cooperating wells formed in the upper shorter edges of the sidewalls for securing the platform removably thereon.

Although the sections comprising the stairs of my invention may be constructed of various materials, I prefer to cast them of reinforced concrete in molds of desired shape. The preformed sections may thereafter be shipped to the site where installation is to be made, and assembled in the manner described hereinbefore.

I claim:

1. A stairway constructed of preformed sections comprising a flat base having spaced wells open to the upper surface thereof, spaced sidewalls mounted detachably on said base and having protruding dowels resting one in each of said wells, said sidewalls having complementary surfaces comprising flat tops and sloping edges, a recess extending laterally in said base and open to said upper surface thereof, one side of said recess forming an extension of the sloping edges of said sidewalls, a plurality of abutting step units each having a riser, a stepping surface and a sloping side, said sloping side resting upon the sloping edges of said sidewalls, a portion of said riser being cut away longitudinally adjacent said sloping side forming a notch with the rear wall of said notch acting as a depending key, the key of the bottom step engaging the recess in the base, the key of intermediate steps abutting against adjacent steps along the side opposite said riser, a platform member resting on said sidewall flat top and abutting the topmost step to form a level surface therewith, and means between abutting sections detachably securing the latter together.

2. A stair constructed of precast sections comprising a base, spaced sidewalls mounted detachably on and abutting said base, said sidewalls having complementary sloping sides, a recess extending laterally in said base, a plurality of abutting steps units each having a riser, a stepping surface and a sloping side, said sloping side resting upon the sloping edges of said sidewalls, a portion of said riser being cut away longitudinally adjacent said sloping side to form a notch with the rear wall of said notch acting as a depending key, each such key extending the full width of one step unit, the key of the bottom step engaging the recess in the base, the key of other units abutting against adjacent units along the side opposite said riser, a platform member abutting the top step and resting across said sidewalls, said

base, step and platform sections having hollow tubes therein aligned with each other, and spike-like connecting means extending through each abutting pair of said hollow tubes and releasably securing said precast sections together.

3. A stair constructed of precast sections comprising a base, spaced sidewalls mounted on said base, said sidewalls having complementary surfaces comprising flat tops and sloping edges, a recess extending laterally in said base, a plurality of step units each having a riser, a stepping surface and a sloping side, said sloping side resting upon the sloping edges of said sidewalls, a portion of said riser being cut away longitudinally adjacent said sloping side to form a notch with the rear wall of said notch acting as a depending key, the key of the bottom step engaging the recess in the base, the key of intermediate units abutting against adjacent units along the side opposite said riser, a platform member resting on said sidewall flat top and abutting the topmost step to form a level surface therewith, said base, platform, and step sections having passages therein aligned with each other, the back of said platform member having an open-faced longitudinal groove therein, a flexible connecting means extending along said platform member groove and through said aligned passages and joined at its ends to form a closed loop releasably securing said sections together, and pin means detachably securing said sidewall and base to complete the joinder of all elements into an integral stair structure.

4. A stair constructed of precast concrete sections comprising a base section, spaced sidewall sections mounted detachably upon and abutting said base, said sidewalls having complementary sloping edges, a recess extending laterally in said base, a plurality of abutting step sections each having a riser, a stepping surface and a sloping side, said sloping side resting upon the sloping edges of said sidewalls, a portion of said riser being cut away longitudinally adjacent said sloping side to form a notch with the rear wall of said notch acting as a depending key, the key of the bottom step engaging and abutting the recess in the base, the key of intermediate steps abutting against adjacent steps along the side opposite said riser, a platform section resting upon and abutting said sidewalls and abutting the top step, and pin means between said abutting base and sidewall, between said abutting bottom step and base, between said abutting platform and sidewalls, and between said abutting steps detachably securing the same together as a structural unit.
